OPEN FRONT SELF-SERVICE
REFRIGERATOR

Paul H. Brinkoeter, San Antonio, Tex., assignor
to Ed Friedrich, Inc., San Antonio, Tex., a cor-
poration of Texas

Application October 23, 1951, Serial No. 252,612

12 Claims. (Cl. 62—89.5)

1

This invention relates to an improvement in open front self service refrigerators, and more particularly to the provision for cooling and circulating of refrigerated air about the contents such as meats and dairy products on display in the refrigerator or cabinet.

The invention consists in a cabinet having front, back and end walls to provide a food compartment and to locate refrigerating cooling means beneath the food compartment.

An object of the invention is to provide blower units at intervals in the cabinet and so disposed with respect to the cooling means to direct air to and through the coils of the cooling means for circulating cold air to the food compartment.

A further object is in the provision of air ducts along the front and back walls of the cabinet so that air may be circulated within the cabinet by the blower units through and over the food compartment, and withdrawn from the food compartment beneath the cooling means, where the air will again be drawn into the cooling means before entering the food compartment.

The invention consists of certain novel features of construction and combinations of parts which will be hereinafter described and pointed out in the claims.

In the accompanying drawings:

Figure 1 is a front view in longitudinal section of the cabinet; Figure 2 is a transverse vertical sectional view of the cabinet on line 2—2 of Figure 1; Figure 3 is a detail view in perspective of the refrigerating coils, showing arrangement with respect to the fans; Figure 4 is a transverse vertical sectional view, similar to Figure 2, but illustrating a modified form of the invention.

The cabinet consists of front and back walls 10 and 11, respectively, and end walls 13. An overhanging wall or super structure 14 extends from the back wall 11 toward the front wall, and is provided with mirrors 15 for displaying the contents of the cabinet.

A plurality of channel shaped cross beams 16—16 extend transversely of the cabinet and are supported by the front and back walls 10 and 11. The cabinet is provided with a lower compartment 18 and a food compartment 20. The front wall 10 is of less height than the back wall 11, and along its upper edge a thermo-pane glass panel 21 is mounted and forms the front wall of the food compartment 20. Doors 22 are provided in the back wall 11 for access to the lower compartment 18.

Mounted on the cross beams 16 are two channel shaped pans 17, 17 which extend lengthwise

of the cabinet and are spaced from each other and from the front and back walls 10 and 11. These pans contain a suitable insulation 19, such as cork and asphalt. Supported on these pans 17 are drip pans 23, 23, preferably channel shaped and which extend lengthwise of the cabinet. Mounted within each drip pan 23 and intermediate the side walls 24 and 25, thereof, is a bank of finned refrigerating or cooling coils 26. 10 The coils 26 are supported above the bottom of the drip pans 23 by a plurality of inverted U-shaped brackets or spacers 27, which are disposed beneath the coils at intervals throughout the length of the coils and cabinet. 15 The inner side walls 25 of each of the drip pans 23 are provided with inwardly extending flanges 28 on which is supported a panel plate 29. The panel plate 29 is provided with openings 30 at intervals in its length for the reception of the fan or fan blades 31 of a fan motor or blower 32. Surrounding the openings 30 and depending from the panel 29 is a circular frame 33 which supports a slotted metal guard 34 beneath the fan blades 31. 20 Extending lengthwise of the refrigerating coils 26 and on each side thereof are inner and outer supporting plates 35 and 36, respectively, which are provided with flanges 37 that overlie the coils 26. The outer plates 36 rest upon the flanges 38 of the spacers 27 and bolts 39 pass through plates 36, flanges 38, pans 23 and 17, and cross beams 16, and these bolts 39 are provided with nuts 40 for securing these elements to the cross beams 16. The inner ends of the spacers 27 are similarly secured to the cross beams 16. The inner supporting plates 35 are connected at their lower ends to the spacers 27 by screws 41. Straps 42 extend across the tops of the coil banks 26 and the ends thereof are bent downwardly 35 against the plates 35 and 36 for additionally holding the finned coils 26 of each bank in position. The insulated pans 17, drip pans 23, and panel plate 29 supported by the cross beams 16 serve as a partition or ceiling for the lower compartment 18. 40 A cover plate 44 extends across the space between the cooling coils 26, and is supported on the upper ends of the inner supporting plates 35. The cover plate 44 is provided with several 45 openings 45 throughout the length thereof for the reception of a portion of the fan motors or blowers 32 mounted in the space between the panel plate 29 and cover plate 44. The blowers are connected to the cover 44 by screws 46. An air chamber 47 is provided between the cooling

50 55

coils 26, the cover plate 30 and the panel plate 29.

The plates 35 and 36 cover the sides of the coils 26 so that air from the blowers is directed under the coils and discharged through the top of the coils 26. The inner plates 35 do not extend to the bottom of the pans 23 so that an air passage is provided from the air chamber 47 beneath the coils throughout their length. The outer plates 36 formed a closure preventing the air from issuing through the coils toward the back and front walls of the cabinet.

The rear wall of the food compartment 20 is provided with a longitudinal duct 48 which is spaced from the rear wall 11 of the cabinet. The duct 48 consists of a rear panel 49 and a front panel 50, the ends and top of which are closed and is supported by an angle iron 51 running full length of cabinet. The lower edges of the panels 49 and 50 are separated and thereby provide an ingress or intake opening to the duct 48. Each panel is provided with an inwardly extending flange, and flange 52 of panel 50 is supported by angle iron 51. Flange 53 of panel 49 is connected to the upper edge of outer supporting plate 36 by screw bolts 54. The front panel 50 of duct 48 is provided with openings or perforations 55 for the egress of the cold air into the food compartment 20, and over the trays or shelves 56. This panel 50 is provided with a longitudinal rib 57 so that the shelves 56 may be elevated and supported in an inclined position, as indicated in dotted lines in Figure 2.

The rear wall 11 of the cabinet has a lining 58 which curves inwardly at its upper end 59 over and above the upper longitudinal edge of the duct 48 for forming an ingress or intake passage or duct 60 between the lining 58 and rear panel 49 to direct the warm air to the lower compartment 18. The side wall 24 of drip pan 23 adjacent rear wall 11 is spaced therefrom to provide an outlet for the passage 60 to the compartment 18. The supporting plate 36 functions as a wall for the passage 60 at its lower end.

A perforated grill or duct 62, extends lengthwise of the cabinet, and is located at the front of the food compartment 20, and is supported on the inner surface of the front wall 10 by a bracket 63. A panel 64, extending longitudinally of the cabinet, is disposed between the outer supporting plate 36 of the front cooling coil 26 and the inner surface of the front wall 10, and is connected to the bracket 63 and underlies an inwardly extending flange 65 of the grill or duct 62, at its upper edge. The lower edge of the panel 64 is connected to a side wall 24 of the drip pan 23 by screw bolts 66. The panel 64 is spaced from the front wall 10 so that a passage or duct 68 is formed leading from the duct 62 to the lower compartment 18. The panel 64 is perforated at 69 to admit cold air from the front cooling coil 26 to a passage 70 disposed between the supporting plate 36 and panel 64 to enter the passage 68 and assist in conducting the warm air from food compartment 20 entering duct 62 to the compartment 18.

The forward edge of the tray or shelf 56 is supported on the brackets 63 and flange 65 of the duct 62, and the rear edge is supported by angle iron 51 and flange 52.

In operation of the device, air is drawn by the blowers 32 into the air or blower chamber 47 from the lower chamber 18 through the openings 30 of panel plate 29, where it builds up pressure and is forced uniformly beneath the lower edges 75

of supporting plate 35 and beneath the two banks of coils 26, where the air will be directed to and through the cooling coils. The air upon leaving the coils is directed beneath the shelf units 56. The perforated shelves 56 are preferably made in units which when positioned in the cabinet make up a single shelf extending the full length and width of the cabinet, and as the refrigerated air from the cooling coils 26 is discharged beneath these shelves throughout the length of the cabinet, the space beneath the shelves provides a large cooling chamber 72 for the shelves and the merchandise supported thereon. From this chamber 72 the refrigerated air, which is under pressure, will be caused to flow into rear duct 48, and from which the air will be exhausted over the top of the shelves or shelf and the merchandise displayed thereon through the openings 55 in the front panel 50 of the duct 48. In this manner the merchandise on the shelf 56 will be maintained in a chilled state, as the shelf will be first subjected to the refrigerated air, and some of the air will flow through the openings or perforations of the shelf and among the merchandise and be expelled over the top of the merchandise. This air emanating through the merchandise will be commingled with the refrigerated air issuing over the top of the merchandise from the duct 48 so that the temperature of the air issuing from the merchandise will be lowered and the merchandise will always be maintained at a proper temperature. In instances where the merchandise is of a character where the perforations of the shelf 56 are substantially closed the merchandise will be cooled by conduction.

The air above the merchandise will be drawn into the lower chamber 18, by suction created by the blowers 32, through the ducts or passages 60 and 62 at the rear and front sides of the cabinet. The large lower compartment 18 is refrigerated by drawing the cold air from the front coil 26 through the passage 70, perforations of panel 64 and passage 63. The warm air drawn from the food compartment 20 through duct 52 and passage 68 is lowered in temperature as it enters the lower chamber 18 by commingling with the refrigerated air issuing into passage 63 from front coil 26.

The cross beams 16 taper inwardly from the ends providing a low area or somewhat concave surface at the center line longitudinally of the cabinet, and therefore the drip pans 23 tilt or are inclined toward the center of the cabinet. This construction allows any moisture or water from the coils, and in the defrosting cycle, to collect in the drip pans 23 and to flow toward the inner side walls 25 of the drip pans, where the water can be readily drained from the drip pans 23 by applying suitable taps to the side walls 25 and conducting the water from the cabinet. Also, as the air is delivered to the coils 26 from the chamber 47, the water in the pans 23 will be collected and evaporated by the air as it is conducted to and forced through the coils 26. The brackets or spacers 27 are so constructed as to support and maintain the coils on a proper level and horizontal plane above the cross beams.

The insulation 19 in the pans 17 prevent the drip pans 23 supported thereabove from sweating, and any condensation from dropping down on the merchandise in the lower compartment 18.

The disclosure in Figure 4 is similar in most respects to that illustrated in the other figures. However, the cooling coils 26 are composed of a single bank of coils extending lengthwise and

transversely of the cabinet. The supporting plates 36, 36 of the coils are supported by angle irons 75 running the full length of the cabinet. The fan motors 32 are supported by a mounting panel 76 that is held in position by the coil assembly in any suitable manner. The fan blades 31 of the motor blowers 32 are located beneath the cooling coils 26 and in the lower compartment 18. A perforated cover plate 77 is disposed above the cooling coils 26 so that the cold air emanating from the coils will be delivered to the cooling chamber 72 provided between the perforated shelf 56 and cover plate 77.

The air duct 62 along the front wall is provided by a panel 78 supported in spaced relation to the front wall 10, and has a glass baffle 79 along its upper edge, which baffle and panel form the front wall of the food compartment 20. The air duct 62 has communication with the cooling chamber 72 and food compartment 20. The air duct 48 along the rear wall has communication with the cooling chamber 72 and food compartment, and the duct 60 forms a communication between the compartments 18 and 20. The perforated shelf is supported by a flange 51 of the front panel 50, and by a flange 80 on the panel 78. A longitudinal sectional partition 81 is supported by the angle irons 75 and is located beneath the cooling coils 26. The partition 81 is recessed or concaved so that any condensate from the coils will drain toward the longitudinal center flanges 83 of each section of the partition. Openings 82 are formed in the partition beneath the fans 31 or blowers 32 to provide communication between the coils 26 and compartment 18.

In this exemplification of the invention the refrigerating coils are located beneath the food display shelf 56 and disposed over the entire shelf area, so that the air forced through the coils 26 will pass through the perforated cover plate 77 into the cooling chamber 72 beneath the shelf 56. The shelf 56 is perforated; so that the air can filter up through the shelf in between the packages of merchandise displayed on the shelf. Should the shelf become completely blocked with merchandise, then the air would travel through the ducts 48 and 62 and be directed in its flow over and into the food compartment 20. Under most conditions the cold air will pass from the cooling chamber 72 through the shelf 56 and ducts 48, 62 to the food compartment 20. The warm air of the food compartment will be withdrawn through duct 60 by the fan blowers 32 into the compartment 18 beneath the coils 26, where it will be again directed through the coils 26 and cooled before entering the food compartment.

While it has been related that the invention as set forth in the several figures is applicable to open self-service refrigerators, it will be readily apparent that the cooling system can be efficiently employed with closed service refrigerators. In the disclosures as set forth in Figures 1 to 3 and Figure 4, the refrigerated air from the cooling coils will be delivered to the cooling chamber 72, and filters up through the perforated shelf 56 around the merchandise displayed thereon and cooling the display area of the food compartment as the refrigerated air passes through the display area to the return air ducts 60 and 62. Should at any time, the display shelf 56 become completely blocked with merchandise in such a manner to prevent the filtering of the refrigerated air through the perforations of the shelves 56, then, the refrigerated air is directed

to the rear air duct 48, as in Figures 1 to 3, and both ducts 48 and 62 of Figure 4, and is expelled over the top of the merchandise cooling the display area of the food compartment.

5. What I claim is:

1. In a display cabinet, the combination of a lower compartment and a food compartment, a shelf between said compartments for displaying merchandise, refrigerating coils located beneath 10 said shelf, blowers for directing refrigerated air from said coils to and through said shelf and food compartment, air ducts located along the front and rear sides of said shelf for conducting cold air from said coils to said food compartment and warm air from said food compartment to said lower compartment, and a partition disposed between said refrigerating coils and lower compartment having an opening therein to provide communication between said lower compartment and said refrigerating coils, said blowers drawing the air from said lower compartment to said refrigerating coils.
2. In an open front display cabinet, the combination of a food compartment having a per- 25 forated shelf for displaying merchandise, refrigerated cooling coils extending lengthwise of said cabinet and arranged beneath said shelf and in spaced relation thereto to provide a cooling chamber between said shelf and cooling coils, 30 blowers for directing air through said coils and into said cooling chamber, and ducts positioned at the front and rear of said food compartment having communication with said cooling chamber and food compartment to provide a circuit 35 for the circulation of air from and to said cooling chamber and said food compartment.
3. In an open front display cabinet, the combination of a food compartment having a per- 40 forated shelf for displaying merchandise, cooling coils extending lengthwise of said cabinet arranged adjacent the front and rear walls of said cabinet, a cover disposed between said cooling coils for forming an air chamber between said cooling coils, blowers for directing air into 45 said air chamber and to said cooling coils, and ducts positioned at the front and rear of said cabinet having communication with said air chamber and food compartment to provide a circuit for the circulation of air from and to said air chamber and said food compartment.
4. In a display cabinet, the combination of a lower compartment and a food compartment, a perforated shelf between said compartments for displaying merchandise, banks of refrigerating 55 coils located beneath said shelf, blowers disposed between said banks of coils, a cold air duct located along the rear side of said shelf for directing cold air over said shelf having communication with said refrigerating coils, and ducts positioned along the front of said cabinet and in rear of said cold air duct having communication with said lower compartment, said blowers drawing the warm air into said lower compartment through said last mentioned ducts.
5. In a display cabinet, the combination of a lower compartment and a food compartment, a shelf between said compartments for displaying merchandise, banks of refrigerating coils located 60 beneath said shelf, blowers disposed between said banks of coils, a cold air duct located along the rear side of said shelf for directing cold air over said shelf having communication with said refrigerating coils, and ducts positioned along the front of said cabinet and in rear of said cold

air duct having communication with said lower compartment, said blowers drawing the warm air into said lower compartment through said last mentioned ducts, and means for conducting refrigerated air from at least one of said coils to said front air return duct.

6. In a display cabinet, the combination of a lower compartment and a food compartment, a partition dividing said lower compartment from said food compartment having an opening therein, a blower chamber extending lengthwise of said cabinet having communication with said lower compartment through said partition, a blower in said blower chamber, cooling coils disposed on each side of said blower chamber having communication with said blower chamber, a shelf for merchandise mounted in said cabinet above said cooling coils and blower chamber providing a cooling chamber therebetween, and a cold air duct located along the rear side of said shelf connected to said cooling chamber for directing cold air across said shelf and cabinet.

7. In a display cabinet, the combination of a lower compartment and a food compartment, a partition dividing said lower compartment from said food compartment having an opening therein, a blower chamber extending lengthwise of said cabinet having communication with said lower chamber through said partition, a blower in said blower chamber, cooling coils disposed on each side of said blower chamber having communication with said blower chamber, a shelf for merchandise mounted in said cabinet above said cooling coils and blower chamber providing a cooling chamber therebetween, and a cold air duct located along the rear side of said shelf connected to said cooling chamber for directing cold air across said shelf and cabinet, and ducts positioned along the front and rear sides of said cabinet having communication with said lower and food compartments, said blower drawing the warm air from said food compartment into said lower compartment through said last mentioned ducts.

8. In a display cabinet, the combination of a lower and a food compartment, a partition between said compartments, a blower chamber having communication with said lower compartment through an opening in said partition, a blower in said chamber, cooling coils disposed on each side of said chamber and having communication with said chamber, a cold air duct and an air return duct mounted along the rear and front walls of said cabinet, a shelf supported by said ducts above said cooling coils and chamber, one of said ducts having communication with said cooling coils and food compartment and the other of said ducts having communication with both compartments.

9. In a display cabinet, the combination of a lower and a food compartment, a partition between said compartments, a blower chamber having communication with said lower compartment through an opening in said partition, a blower in said chamber, cooling coils disposed on each side of said chamber and having communication with said chamber, a cold air duct and an air return duct mounted along the rear and front walls of said cabinet, a shelf supported by said ducts above said cooling coils and chamber, one of said ducts having communication with said cooling coils and food compartment and the other of said ducts having communication with

both compartments, and another air return duct having communication with both compartments and disposed between the rear wall of said cabinet and said cold air duct.

10. In a display cabinet, the combination of a lower compartment and a food compartment, a partition in said cabinet between said compartment, cooling coils extending lengthwise of said cabinet along the front and rear walls thereof, supported by said partition, blowers between said coils, a cover plate extending lengthwise of said cabinet and bridging the space between said coils for forming with said partition a blower chamber, said blower chamber having communication with said lower chamber and with said cooling coils, a cold air duct and air return ducts mounted along the rear and front walls of said cabinet, a shelf supported by said ducts above said cooling coils and said chamber, said cold air duct having communication with said cooling coils and said food compartment, said air return duct having communication with both compartments, and means for conducting refrigerated air to said air return duct to be directed into said lower compartment with the warm air from the food compartment.

11. A display cabinet, comprising a front wall and a back wall, and a food compartment and a lower compartment, drip pans extending lengthwise of said cabinet and spaced from said front and back walls and separated from each other, refrigerating coils mounted in each of said drip pans and disposed above the bottom of said pan, a panel plate extending lengthwise of said cabinet located between said pans and supported thereby, said pans and panel plate separating said food compartment from said lower compartment, a blower disposed between said refrigerating coils having communication with said lower compartment for delivering air therefrom to said coils, a cold air duct and an air return duct mounted along the rear and front walls of said cabinet, a shelf supported by said ducts, said cold air duct having communication with said coils and food compartment, said air return duct having communication with both compartments.

12. In a display cabinet, comprising a front wall and a back wall, and a food and a lower compartment, insulated drip pans arranged in parallel relation and spaced from said front and back walls supported in said cabinet, cooling coils mounted in said drip pans and supported above the bottoms thereof, outer supporting plates mounted in said pans and engaging the outer sides of said coils, inner supporting plates engaging the inner sides of said coils and having the lower edges thereof spaced from the bottom of said pans to provide an air passage to said pans and coils, a blower for delivering air from said lower compartment to said coils, a shelf in said food compartment located above said coils, an air duct for delivering cold air from said coils to said food compartment, and an air return duct having communication with both compartments.

PAUL H. BRINKOETER.
